UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,337,681.

Specification of Letters Patent. Patented Apr. 20, 1920.

Application filed March 29, 1917. Serial No. 158,231.

To all whom it may concern:

Be it known that I, SAMUEL B. WILLIAMS, Jr., a citizen of the United States, residing at Brooklyn, in the county of Kings and State of New York, have invented certain new and useful Improvements in Telephone-Exchange Systems, of which the following is a full, clear, concise, and exact description.

10 This invention relates to telephone exchange systems, and more particularly to call distributing systems employing line finder switches.

15 It is the object of this invention to provide a system in which power-driven switches may be used, and in which line finder switches are arranged to be controlled in group, subgroup and line selection.

20 A further object of this invention is to provide a call distributing system in which an operator's position is made non-selectable when a certain amount of work is stored up at such position.

25 It is an additional object of this invention to provide a call distributing system in which the calling lines may terminate in various sections of a contact bank, the arrangement being such that when a call is initiated an idle operator's position is selected, whereupon an allotted finder arranged to extend the calling line to said selected operator's position may be started in search of the calling line, means being necessarily present to control the starting of a finder which has access to the proper section of the panel bank.

30 A feature of the invention is an arrangement in which line finder switches of the panel type accomplish group and subgroup finding, in accordance with registrations set up in response to the electrical conditions of the group and subgroup relays individual to the group and subgroup in which the calling subscriber's line is located.

35 An additional feature of the invention is an arrangement by which counting relays are actuated at an operator's position in response to the calls incoming to such position as long as it is selectable.

40 A further feature of the invention is an arrangement by which an operator's position is rendered non-selectable when she has two calls stored up at her position, the position also being non-selectable if she has one

call stored up and is listening in on another 55 call.

It is thought that the invention will best be understood from the following detailed description, reference being had to the accompanying drawings.

Referring now to the drawings, Figure 1 shows calling subscribers' lines with the group and sub-group relays common to certain ones of such lines; Fig. 2 shows the circuits of a line finder switch and a connecting 65 operator's cord circuit; Fig. 3 shows controlling circuits for setting the line finder switch of Fig. 2 and the relays by means of which an operator's position may be selected, together with an allotter switch 70 which determines which one of a plurality of line finders shall be started after a position has been selected; Fig. 4 shows duplicate apparatus at two operators' positions, and illustrates the arrangement by which 75 starting circuits from the various sections may put into operation the desired apparatus at a selectable operator's position.

In Fig. 3 the sequence switch contacts shown within the dotted lines in the lower 80 left-hand portion of the drawing are controlled by the sequence switch 200 associated with them, the remaining sequence switch contacts shown in this figure being controlled by an allotting sequence switch 300. 85 The sequence switch contacts shown in Fig. 2 are controlled by the line finder sequence switch 400.

The general arrangement of the system is as follows. If we assume that there are 90 twenty-five hundred calling lines to be served by the operators and that these calls are to be extended to such operators by means of line finder switches each having a capacity of five hundred lines, the lines will 95 be arranged in five sections of panel bank, each of five hundred lines capacity. There will be a plurality of line finders serving each section of the panel bank and their arrangement must be such that a calling line 100 may be extended to any operator's position. Therefore, the line finders associated with each section are divided into as many groups as there are operators' positions. When a call is originated an idle operator's position 105 will be automatically selected, as will be subsequently described, and then, by means of an allotter switch, an idle switch in the

proper section of panel bank will be started to extend the call to the selected operator's position.

Each section of five hundred lines is divided into five main groups of one hundred lines each which may be selected in response to the brush selecting operation of the line finder switch. Each group of one hundred lines is divided into four sub-groups of twenty-five lines each. The sub-group of twenty-five lines is selected in response to the group selecting movement of the line finder switch, and the individual terminal set in the selected group is selected by a simple hunting movement.

In Fig. 1 are shown the lines of four calling subscribers. Of the substations indicated, 1 and 2 belong to the same main group of the one hundred lines, which has been shown as the first main group, while the substations 3 and 4 belong to another main group of one hundred lines which has been shown as the fifth main group. Stations 1 and 3, however, both belong to corresponding sub-groups of their respective main groups, and therefore their sub-group relays control a common point on the recording apparatus shown in Fig. 3. Similarly, substations 2 and 4 are located in corresponding sub-groups of their respective main groups and therefore control another common point on the recording apparatus shown in Fig. 3.

Assuming that the subscriber at substation 1 desires to make a call he will remove his receiver from the hook, whereupon line relay 5 will be energized over a circuit from grounded battery, left-hand winding of line relay 5, outer left-hand armature and back contact of cut-off relay 6, the loop of the calling line, the inner armature and back contact of cut-off relay 6, right-hand winding of relay 5, to ground. Relay 5 upon energization completes a circuit from grounded battery, armature and back contact of relay 7, upper right-hand armature and back contact of relay 8, contact 9, armature and front contact of relay 5, to ground. Contact 9 is controlled by a sequence switch 100, there being one of these sequence switches associated with each sub-group of calling lines for a purpose to be hereinafter described. Relay 8 is energized in the above traced circuit and locks up over a path from grounded battery, winding of relay 7, lower right-hand armature and back contact of relay 8' (corresponding to relay 8), lower right-hand armatures and back contacts of other relays of the main group corresponding to relay 8, right-hand armatures of relay 8, winding of relay 8 contact 9, armature and front contact of relay 5, to ground. It is thus obvious that only one call may be initiated in a main group at a time, since, if any relay corresponding to 8 is energized,

the energization of relay 7 in the locking circuit of such relay will prevent any other corresponding relay from being energized. The energization of relay 7 completes a circuit from grounded battery, armature and front contact of relay 7, winding of relay 10, upper right-hand armature and back contact of relay 10 upper armature and back contact of relay 11, lower armature and back contact of relay 12, to ground. Relay 10 is energized in this circuit and locks up over a circuit from ground, lower armature and back contact of relay 12, winding of relay 11, lower right-hand armature and back contact of relay 10' (corresponding to relay 10), lower right-hand armatures and back contacts of other relays corresponding to relay 10, there being one such relay for each main group, conductor 13, the right-hand armatures of relay 10 in an actuated condition, winding of relay 10, armature and front contact of relay 7, to grounded battery. Relay 11 is energized in this circuit and prevents the energization of any other main group relay corresponding to 10, since at its upper armature it opens the circuit over which all such relays are initially energized. The energization of relay 11 completed a circuit from grounded battery, winding of relay 28, left-hand armature and front contact of relay 10, the lower armature and front contact of relay 11, to ground. Relay 29 is thereupon energized over a circuit from grounded battery, winding of relay 29, left-hand armature and front contact of relay 8, to ground at the left-hand armature and front contact of relay 28. The energization of relay 29 supplies ground at its right-hand armature and front contact for operating the sub-group registering apparatus shown in Fig. 3, as will be subsequently described.

The energization of relay 11 also completes a circuit from ground, lower armature and back contact of relay 12, upper armature and front contact of relay 11, conductor 14, winding of relay 15, to grounded battery. Relay 15 is energized, whereupon a circuit is completed from grounded battery, lower armature and back contact of relay 16, upper right-hand armature and back contact of relay 17, winding of relay 17, armature and back contact of relay 18, armature and front contact of relay 18', armature and front contact of relay 15, to conductor 14, and ground. This starting circuit is extended from ground through the armatures and front contacts of relays 18' associated with busy operators' positions which are in a nonselectable condition, and the call is extended to the first position at which a relay, in this case assumed to be the relay 18, is in a non-actuated condition to indicate the non-busy condition of the operator's position.

Relay 17 upon energization locks up in a circuit from grounded battery, winding of relay 16, the lower right-hand armatures and back contacts of section-selecting relay 5 17' corresponding to relay 17, conductor 20, the right-hand armature of relay 17 in an actuated condition, and the winding of relay 17 to ground over the path described.

It is to be understood that there is a 10 starting circuit similar to the one described associated with each five hundred line section of finders, and that there are position selecting relays corresponding to relays 18 and 18' associated with each such starter 15 circuit. As shown in Figs. 3 and 4, the starting circuits of three sections have been indicated at two operators' positions. It is obvious that while one of the relays 17 is energized, it will be impossible to energize 20 another corresponding relay due to the actuated condition of the common relay 16.

The registering and sending equipment indicated within the dotted line in the lower left-hand portion of Fig. 3 is associated 25 with the allotter switch 300. It will be understood that there are at each operator's position as many allotting sequence switches 30 indicated in the lower left-hand portion of Fig. 3 is permanently associated with each such allotter.

It will be seen therefore that by means of the relays 18 an idle position may be selected. In response to the selection of an operator's position, a relay corresponding to relay 17 will be energized to control the starting of an allotter finder. The finders serving each section of panel contact bank 40 are divided into groups, there being as many groups as there are operators' positions. Therefore, the particular relay 17 which was energized will determine in which section of contact bank and in which group 45 of finders an allotted finder will be started.

In case all the operators' positions are busy, a circuit will be completed from grounded battery, winding of relay 21, front contact and armature of relay 18, which 50 has been shown as the last in the chain, through the front contacts and armatures of position selecting relays corresponding to relays 18 and 18', front contact and armature of relay 15, to ground over the path 55 described. The energization of relay 21 completes a circuit for lamp 22 from grounded battery, lamp 22, armature and front contact of relay 21 to ground. The lighting of this lamp will enable a count to 60 be made of the number of times the busy condition of all operators' positions arises.

Relay 17 upon energization completed a 65 circuit from grounded battery, winding of relay 23, left-hand armature and front contact of relay 17 to ground. A circuit is

then completed from grounded battery, power magnet of sequence switch 400, contact 402, conductor 403, allotter contact 302, upper armature and front contact of relay 23 to ground, for moving the sequence switch 70 400 out of position 1 into position 2 under the control of its normal spring 401.

When sequence switch 400 arrives in position 2, a circuit is completed from grounded battery, power magnet of sequence switch 75 200, contact 202, conductor 24, allotter contact 303, conductor 304, contact 404, to ground, for moving this sequence switch out of position 1 and into position 3, under the control of its master contact 201. While 80 sequence switch 200 was passing through positions 1 $\frac{1}{2}$ to 2, a circuit was completed from grounded battery, winding of relay 27, contacts 204 and 205, conductor 206 to ground at the right-hand armature and 85 front contact of relay 29. The relay 27 is energized to control the sub-group selection in a manner to be subsequently described.

When sequence switch 200 arrived in position 3, a circuit was completed from 90 grounded battery, winding of relay 26, left-hand armature and back contact of relay 30, contact 207, conductor 208, to ground at the left-hand armature and front contact of relay 28. Relay 26 is energized in this 95 circuit and prevents the further advance of sequence switch 200. If the call had been originated in some other main group, for instance, the main group including the subscribers whose substations are indicated at 100 3 and 4, sequence switch 200 would have been moved out of position 3 over a circuit from grounded battery, power magnet of sequence switch 200, contact 203, conductor 25, allotter contact 305, conductor 306, contacts 405 and 406, conductor 407, allotter contact 307, right-hand armature and back contact of relay 26, and would have advanced into a position determined by which 105 one of the main group relays corresponding to relay 28 had been energized. For instance, if relay 28' had been energized, the sequence switch 200 would have advanced into position 7, since relay 26 would not have been energized to break the above 110 traced circuit until sequence switch 200 arrived in position 7. In this case the energizing circuit of relay 26 would have been extended from grounded battery, winding of relay 26, left-hand armature and back 115 contact of relay 30, contact 209, conductor 210, left-hand armature and front contact of relay 28', to ground.

The switch 200 operates both as a register and as a sender, its sending function being accomplished on the complement basis, that is, it will move to an end position in every case and if the fifth brush is to be selected, it will be stopped in an early position so that five impulses will be sent to 125 130

the line finder switch during brush selection. However, if the first brush is to be selected, the switch 200 will be stopped in a position just before its end position and thus only one impulse will be sent.

- When relay 26 is energized, a circuit is completed from grounded battery, power magnet of sequence switch 400, contact 408, conductor 409, allotter contact 310, contact 210, armature and front contact of relay 26, to ground, for moving sequence switch 400 out of position 2 and into position 3. With sequence switch 400 in position 3, a circuit is completed from grounded battery, winding of relay 12, conductor 31, allotter contact 308, conductor 309, contact 410, to ground. Relay 12 is energized and at its lower armature removes ground from a starter wire 14, whereupon relays 15, 17 and 16 are deenergized. The unactuated condition of relay 16 will now permit another call from the same or some other section to be extended to the selecting relays 17' corresponding to relay 17.
- Relay 12 at its lower armature also removed ground from the windings of relays 10 and 11, causing their deenergization. Relay 10 causes in turn the deenergization of relay 28, but this relay being slow to release, maintains its armatures attracted for a sufficient period of time for a circuit to be completed from grounded battery, winding of a timing sequence switch 100, contact 102, left-hand armature and front contact of relay 29, right-hand armature and front contact of relay 28, lower armature and front contact of relay 12, to ground. The timing sequence switch 100 is then moved out of position 1 and moves through a complete cycle of rotation under the control of its master contact 101, holding open at its contacts 9, the circuits of sub-group relays corresponding to relay 8, and thus prevents the sub-group from starting other line finders for a time interval of sufficient length to permit the selection of the topmost line of any multiple bank. All succeeding calls in the sub-group are held up during this time interval.
- With the relay 12 energized, a circuit is also completed from grounded battery, power magnet of sequence switch 400, contact 411, conductor 412, allotter contact 311, conductor 312, upper armature and front contact of relay 12, conductor 31, allotter contact 308, conductor 309, contact 410, to ground, for moving this sequence switch out of position 3 and into position 4.

With sequence switch 400 in position 4, the fundamental circuit is completed from grounded battery, winding of relay 32, contacts 413, 414, conductor 415, allotter contact 313, winding of stepping relay 33, contact 211 to ground. Relays 32 and 33 are energized in this circuit, relay 32 complet-

ing a locking circuit for itself by way of its right-hand armature and front contact and contact 414, to conductor 415, and at its left-hand armature completing a circuit from grounded battery, power magnet of sequence switch 400, contact 416, left-hand armature and front contact of relay 32 to ground, for moving this sequence switch out of position 4 and into position 5.

In position 5 of sequence switch 400, a circuit is completed from grounded battery, winding of low-speed up-drive magnet 34, contact 417, left-hand armature and front contact of relay 32, to ground. Magnet 34, upon energization, presses the driving ribbon 35 into engagement with a roller 36 constantly rotating in the direction indicated by the arrow, and causes the elevation of a brush shaft 37 carrying a plurality of brush sets, similar to the one indicated at 38, in an upward direction.

The mechanical structure of the switch shown in Fig. 2 is somewhat similar to the structure of the switch shown in Patent No. 1,123,696, issued to E. B. Craft and J. N. Reynolds, and is of the type in which a plurality of normally inoperative brush sets are mounted on a brush-carrying shaft, the shaft being arranged to be advanced into a position wheréin a desired brush set may be rendered operative, after which such operated brush set may be advanced in a group-selecting movement, and subsequently in a line-selecting movement.

When sequence switch 400 arrived in position 4, a circuit was completed for relay 30 from grounded battery, winding of relay 30, allotter contact 314, conductor 315, contact 418, to ground, and this relay locked up over a path from grounded battery, winding of relay 30, right-hand armature and front contact of such relay, contact 212, to ground.

When stepping relay 33 was first energized, a circuit was completed from grounded battery, winding of relay 26, left-hand armature and front contact of relay 30, contacts 213 and 214, right-hand armature and back contact of relay 39, armature and front contact of stepping relay 33 to ground. Relay 26 was energized in this circuit and completed a circuit from grounded battery, power magnet of sequence switch 200, contact 203, conductor 25, allotter contact 305, conductor 306, contacts 405 and 419, closed in position 5 of sequence switch 400, conductor 409, allotter contact 310, contact 210, armature and front contact of relay 26, to ground, for moving this sequence switch out of position 3 and into position 4.

When commutator brush 40 engages the first conducting segment of a commutator 41, a circuit in shunt of the fundamental circuit is completed from grounded battery, winding of relay 32, right-hand armature and front contact of relay 32, conductor 50,

contact 420, conducting segment of commutator 41, brush 40, to ground. Stepping relay 33 is shunted out by this circuit and deenergizes, causing in turn the deenergization 5 of relay 26. The driving circuit of sequence switch 200, which is now operating as a sender, is thus opened at the armature of relay 26 and this sequence switch comes to rest in position 4. The timing of the rate 10 of rotation of sequence switch 200 in relation to the speed at which commutator brush 40 travels over commutator 41 must be such that the sequence switch will arrive at a stopping position a moment after the brush 15 engages the conducting segment of the commutator. Therefore, when the commutator brush 40 moves onto the next insulating segment of the commutator, relay 33 will be again energized and will complete a circuit 20 for relay 26, causing sequence switch 200 to be moved out of position 4 and into position 5.

When sequence switch 200 leaves position 7, at which time the brush shaft 37 will 25 have been advanced five steps, the lower branch of the fundamental circuit is broken at contact 211, and when a moment later, brush 40 engages an insulating segment of commutator 41, the upper branch of the 30 locking circuit of relay 32 is opened and this relay deenergizes, opening at its left-hand armature the circuit of the driving magnet 34 and bringing the brush shaft to rest in a position wherein the fifth set of brushes may 35 be tripped upon the operation of the trip magnet 43. The sequence switch 200 comes to rest in position 9.

The deenergization of relay 32 completed a circuit from grounded battery, power 40 magnet of sequence switch 400, contact 421, left-hand armature and back contact of relay 32, to ground, for moving this sequence switch out of position 5 and into position 6.

In positions 6 and 7 a trip magnet 43 is 45 energized over a circuit from grounded battery, winding of magnet 43, contact 422, to ground. The energization of the trip magnet places a projection in the path of a positioned set of brushes so that upon subsequent upward movement, the desired brush set will be released.

It will be remembered that of the sub-group selection-controlling relays 27, 44, 45 and 46, only relay 27 was energized, and that 55 this relay locked up over a circuit from grounded battery, winding of relay 27, left-hand armature and front contact of relay 27, contact 216, to ground.

Sub-group selection is controlled by a sequence switch 200 on the complement basis in the same manner in which brush selection or main group selection was accomplished, and since the calling line is located, as in the present case, in the fourth group, 60 the sequence switch will not be moved out

of position 9. If, however, the call had originated in the second sub-group, the relay 45 would have been energized and would have locked up to ground at contact 216. In this case sequence switch 200 would have 70 been moved out of position 9 and into position 11 so that two impulses would be sent instead of four, as in the present case. In this case, in position 9 of sequence switch 200, relay 39 would have been energized 75 over a circuit from grounded battery, winding of relay 39, contact 217, right-hand armature and back contact of relay 27, to ground. The energization of relay 39 would then have completed a circuit from 80 grounded battery, power magnet of sequence switch 200, contact 218, left-hand armature and front contact of relay 39, to ground, for moving this sequence switch out of position 9 and into position 10. Relay 39 would have deenergized while sequence switch 200 was passing from position 9 to position 10, but would have again been energized in position 10 of sequence switch 200 over a circuit from grounded 90 battery, winding of relay 39, contact 219, right-hand armatures and back contacts of relays 44 and 27, to ground, and would have completed the previously traced circuit for moving sequence switch 200 out 95 of position 10 into position 11.

As stated, in the present case, sequence switch 200 remains in position 9 until moved out of position 9 under the control of stepping relay 33, upon the reestablishment of the fundamental circuit.

When sequence switch 400 arrives in position 6, the fundamental circuit is reestablished and extends from grounded battery, winding of relay 32, contacts 413, 414, conductor 415, allotter contact 313, winding of stepping relay 33, contact 220, right-hand armature and front contact of relay 27, to ground. Relays 32 and 33 are energized in this circuit. Relay 32 locks up 110 as before and at its left-hand armature completes a circuit from grounded battery, power magnet of sequence switch 400, contact 416, left-hand armature and front contact of relay 32, to ground, for moving 115 this sequence switch out of position 6 and into position 7.

In position 7 of sequence switch 400, a circuit is completed from grounded battery, winding of up-drive magnet 47, contact 423, left-hand armature and front contact of relay 32 to ground. The energization of magnet 47 presses the driving ribbon 35 against the high-speed roller 48 constantly rotating in the direction indicated by the 120 arrow, and causes the brush shaft 37 to be elevated in a group-selecting movement.

Relay 26 was energized in position 9 of sequence switch 200 over a circuit from grounded battery, winding of relay 26, 130

left-hand armature and front contact of relay 30, contacts 213 and 214, right-hand armature and back contact of relay 39, to ground at the armature and front contact 6 of stepping relay 33, when this relay was energized upon the closure of the fundamental circuit.

In position 7 of sequence switch 400, and with relay 26 energized, a circuit is completed from grounded battery, power magnet of sequence switch 200, contact 221, allotter contact 316, conductor 317, contacts 454 and 419, conductor 409, allotter contact 310, contact 210, armature and 10 front contact of relay 26 to ground, for moving this sequence switch out of position 9 and into position 10.

When commutator brush 40 engages the first conducting segment of the commutator 20 49, a circuit in shunt of the fundamental circuit is completed from grounded battery, winding of relay 32, right-hand armature and front contact of relay 32, conductor 50, contact 425, conducting segment of commutator 49, brush 40, to ground. Stepping relay 33 is shunted out in this circuit and deenergizes, causing in turn the deenergization of relay 26. The driving circuit of sequence switch 200, which is again operating 25 30 as a sender, is thus opened at the armature of relay 26, and this sequence switch comes to rest in position 10. The timing of the sequence switch 200, with relation to the speed at which the commutator brush 40 travels over commutator 49, must be the same as in the preceding case, that is, such that the sequence switch will arrive at a stopping position a moment after the commutator brush engages a conducting segment 35 40 of the commutator. Therefore, when the commutator brush 40 moves onto the next insulating segment of commutator 49, relay 33 will be again energized and will complete a circuit for relay 26 to move 45 the sequence switch 200 out of position 10 and into position 11.

When sequence switch 200 leaves position 12, at which time the brush shaft 37 will have been advanced four steps, the lower 50 branch of the fundamental circuit is broken at contact 220 and when, a moment later, brush 40 engages an insulating segment of commutator 49, the upper branch of the locking circuit of relay 32 is opened and 55 this relay deenergizes, opening at its left-hand armature the circuit of the driving magnet 47 and bringing the brush shaft to rest with the fifth set of brushes in a position below the fourth sub-group of terminals. The sequence switch 200, on leaving 60 position 12, completes its cycle of rotation and comes to rest in position 1. On leaving position 12, the locked-up relays 30 and 27 are deenergized, leaving the registering and 65 sending apparatus in a condition for re-

operation. The deenergization of relay 32 completed a circuit from grounded battery, power magnet of sequence switch 400, contact 421, and the armature and back contact of relay 32, for moving this sequence switch 70 out of position 7 and into position 8. In position 8 of sequence switch 400, relay 32 is again energized over a circuit from grounded battery, winding of relay 32, contact 413, contact 426, armature and back contact of relay 51, to ground, and locks up through its right-hand armature. At its left-hand armature, a circuit is completed from grounded battery, power magnet of sequence switch 400, contact 416, left-hand 75 armature and front contact of relay 32 to ground, for moving this sequence switch out of position 8 and into position 9.

In position 9 of sequence switch 400, a circuit is completed from grounded battery, 80 winding of up-drive magnet 47, contact 423, left-hand armature and front contact of relay 32. Magnet 47 is energized to cause the upward motion of brush shaft 37, to cause the selected brush set to hunt for the 90 calling line in the selected sub-group. When the brush set 38, composed of the brushes 151, 52 and 53, engages the terminals of the calling line, relay 54 will be energized over a circuit from grounded battery, winding of 95 relay 54, contact 428, test brush 151, test terminal 55, and the winding of a cut-off relay 6, to ground. Relay 54, upon its energization, completes an energizing circuit for relay 51 through contacts 429 and 430, 100 and the closed loop of the calling substation line. Relay 51 upon energization will open one branch of the locking circuit of relay 32. Relay 32 is maintained energized, however, a moment longer over a path 105 extending through contact 431 and a conducting segment of commutator 56 and brush 57, to ground, until brush 57 engages an insulating segment of commutator 56, at which time the brush set will be accurately 110 centered on the terminals of the calling line. Relay 32 then deenergizes and at its left-hand armature opens the circuit of up-drive magnet 47, bringing the brush set to rest on the terminals of the calling line. 115

While the brush set was passing over the terminals of busy lines, relay 54 could not be energized, due to the reduced ground potential on the test terminals 55 of such lines. When the brush set engaged terminals of non-calling lines, relay 54 was energized, but relay 51 could not be energized, since the line loop through the substation was open, due to the non-calling condition of such line. 120

Relay 32, upon deenergization, also completes a circuit from grounded battery, power magnet of sequence switch 400, contact 421, left-hand armature and back contact of relay 32 to ground, for moving this 125 130

sequence switch out of position 9 and into position 10. In position 10, battery is supplied to test brush 151 and test terminal 55 from grounded battery, resistance 58, through 5 contact 432, to shunt out the testing relay 54 of any other hunting finder, and to prevent the calling line from being seized by any such hunting finder.

In position 10 of sequence switch 400, the 10 calling line conductors are extended to the repeating coil 59 by way of contacts 433 and 434. Supervisory relay 60 is then energized in the well-known manner and completes a circuit from grounded battery, 15 winding of slow-release relay 61, armature and front contact of relay 60, to ground. Relay 61 upon energization completes a circuit from grounded battery, power magnet of sequence switch 400, contact 435, armature and front contact of relay 61, right-hand armature and back contact of relay 62, to ground, for moving this sequence switch out of position 10 and into position 11.

When sequence switch 400 arrives in position 11, a circuit is completed from grounded battery, interrupter 63, contact 436, lamp 64, contact 437, to ground. The lamp 64 is caused to flash in this circuit and informs the operator whose position has 25 been selected that a calling line has been connected to the cord circuit terminating in plug 65. She thereupon depresses listening key 66 associated with such cord circuit, whereupon a circuit is completed from 30 ground, winding of relay 67, closed contacts of key 66, contact 438, and the winding of relay 68, to grounded battery, for energizing relay 68. The listening key 66 was depressed only momentarily and when it assumes 35 its normal position, a locking circuit for the relay 68 is completed from grounded battery, winding of relay 68, its right-hand armature and front contact, winding of relay 69, common to all the cords of a position, closed contacts of listening-out key 70, common to all the cords of a position, through 40 the normal contacts of other listening keys corresponding to 66, one of which is indicated at 71, through the normally closed contacts of key 66, and the winding of relay 67, to ground. With relays 68 and 69 energized, a circuit is completed from grounded battery, winding of relay 72, winding of listening-in relay 73, left-hand armature and 45 front contact of relay 68, left-hand armature and front contact of relay 69, to ground. Relays 72 and 73 are energized in this circuit, relay 72 completing a circuit from 50 grounded battery, power magnet of sequence switch 400, contact 439, outer left-hand armature and front contact of relay 72, to ground, for moving this sequence switch out of position 11 and into position 12.

In position 12 of sequence switch 400, a 55 circuit is completed from grounded battery,

contact 440, lamp 64, inner left-hand armature and front contact of relay 72, to ground, causing this lamp to burn steadily and indicating to the operator that her headset has been connected to the calling line. 70 The energization of relay 73 causes the operator's headset indicated at 74 to be connected to the tip and ring conductors of the cord circuit, and the operator may enter into telephonic communication with the calling subscriber in order to ascertain the number of the wanted line. After learning the number of the wanted line, the operator will depress listening-out key 70, causing the deenergization of relay 69 and the unlocking of relay 80 75 68. The deenergization of relay 69 causes in turn the deenergization of relays 72 and 73. The deenergization of relay 73 disconnects the operator's headset from the cord circuit. The deenergization of relay 72 causes lamp 64 to be extinguished.

After learning the number of the wanted line, the operator will insert plug 65 into a jack 76 in which the desired line terminates, whereupon a circuit will be completed from 90 grounded battery, winding of relay 62, sleeve contacts of plug 65 and jack 76, to ground through the cut-off relay of the called subscriber's line which corresponds to cut-off relay 6 shown in Fig. 1. Relay 95 62 and the cut-off relay of the called line are energized in this circuit, the cut-off relay of the called line operating to remove the control of the called subscriber's line relay in the well-known manner.

The operator will then depress a ringing key 77 to connect ringing current with the line of the called subscriber. Upon the release of the ringing key and after the called subscriber answers, supervisory relay 78 will 100 105 be energized in the well-known manner over the called subscriber's line.

Upon the termination of the conversation and after the calling and called subscribers have replaced their receivers, supervisory 110 relays 60 and 78 are deenergized. A circuit is then completed from grounded battery, answering supervisory lamp 779, contact 441, armature and back contact of relay 60, to ground. At the same time the deenergization of relay 78 completed a circuit from 115 grounded battery, calling supervisory lamp 80, left-hand armature and front contact of relay 62, armature and back contact of relay 78, to ground. The operator is informed 120 by the lighting of these well-known signals that connection is no longer desired, whereupon she removes plug 65 from jack 76, causing the deenergization of relay 62. The deenergization of relay 60 opened the circuit 125 of relay 61 and this relay deenergizes. A circuit is then completed from grounded battery, power magnet of sequence switch 400, contact 442, armature and back contact of relay 61, right-hand armature and back con- 130

tact of relay 62, to ground, for moving this sequence switch out of position 12 and into position 14.

- With sequence switch 400 in position 14, 5 a circuit is completed from grounded battery, down-drive magnet 79, contact 443, to ground. Downdrive magnet 79 is energized and presses driving ribbon 35 into engagement with a roller 80, constantly rotating in 10 the direction indicated by the arrow, and causes the brush rod 37 to be restored to its normal position. When the brush rod arrives in its normal position, a circuit is completed from grounded battery, power magnet 15 net of sequence switch 400, contact 444, a normal conducting segment 81, brush 82, to ground, for moving this sequence switch out of position 14 and into its normal position under the control of master contact 401. 20 When the sequence switch 400 leaves position 14, the energizing circuit of magnet 79 is broken at contact 443.

- Referring now to that point in the operation at which sequence switch 400 arrived 25 in position 8, it will be noted that upon the arrival of sequence switch 400 at position 8, a circuit was completed from grounded battery, winding of relay 83, allotter contact 318, conductor 319, contact 445, to ground. 30 Relay 83 is energized in this circuit and completes a circuit from grounded battery, power magnet of allotter 300, contact 320, left-hand armature and front contact of relay 83 to ground, for moving this allotter 35 out of position 1 and into a position to allot the next idle finder. If when sequence switch 300 arrives in position 3, which is the next allotting position, a circuit is again closed for relay 83 by way of allotter contact 40 321, corresponding to contact 445 at the finder switch which is controlled in position 3 of the allotter, the allotter will be advanced out of position 3 in a manner similar to that described and into position 5. If a 45 finder switch has been restored to normal, but the plug has not been withdrawn from the jack, the finder will still test busy to the allotter, since in this case the circuit of relay 83 will be extended from conductor 50 319 by way of conductor 446, to ground, at the right-hand armature and front contact of relay 62. If all the finders are busy, the allotter 300 will be moved into position 15, in which position it will remain until one of 55 the finders arrives in position 1, whereupon a circuit will be completed from grounded battery, power magnet of allotter 300, contact 322, through one of the multiple leads corresponding to 323, a contact correspond- 60 ing to contact 447 at the finder which has returned to its normal position, to ground. The allotter will then be moved out of position 15 and into position 1, whereupon it will test until the idle finder has been found

and allotted for use. It is to be observed 65 that while the allotter is resting in position 15 a circuit is completed from grounded battery, winding of position-selecting relay 18 associated with the position with which the allotter is associated, and contact 448 to 70 ground. Relay 18 is energized in this circuit to produce a non-selectable condition at its associated operator's position.

When the calling line was first extended to the operator's position by means of 75 starter wire 14, relay 16 also energized. If, now we assume that at this time the operator's position was idle, the energization of relay 16 will complete a circuit from grounded battery, winding of counting relay 84, armature and back contact of counting relay 84', conductor 85, to ground at the upper armature and front contact of relay 16. Relay 84 is energized and prepares a 80 circuit for relay 84' so that when relay 16 is 85 deenergized upon the release of the starting circuit when sequence switch 400 arrives in position 3, relay 84' will be energized over a 90 circuit from grounded battery, winding of relay 84, armature and front contact of relay 84, winding of relay 84', and the back contact and armature of relay 86, to ground.

If, before the operator listens in on the first call, another call is extended to her position, the second energization of relay 16 95 will complete a circuit from grounded battery, winding of counting relay 87, the outer left-hand armature and back contact of counting relay 87', the inner lower armature 100 and back contact of relay 67, and the left-hand armature and front contact of counting relay 84', conductor 85, to ground at the upper armature and front contact of relay 16. Relay 87 is energized in this circuit and prepares a circuit for relay 87', so that upon 105 the deenergization of relay 16 in response to the release of the starting circuit which caused its actuation relay 87' will be energized in a circuit from grounded battery, winding of relay 87, armature and front 110 contact of relay 87, winding of relay 87', armature and back contact of relay 88, to ground. With the counting relays 84' and 87' energized, a circuit is completed for relay 89 from grounded battery, winding of 115 relay 89, inner right-hand armature and front contact of relay 87' to ground. Relay 89 is energized and completes a circuit from grounded battery, winding of relay 18, contact 324, conductor 325, left-hand armature 120 and front contact of relay 89, to ground. Relay 18 is energized in this circuit and attracts its armature to extend the position-selecting starter wire and render the position non-selectable. Therefore, no more 125 calls can reach the operator's position until some of the work stored up has been handled.

When the operator listens in on the first call, the energization of relay 67 completes a circuit from grounded battery, winding of relay 90, right-hand armature and back contact of relay 69, upper armature and front contact of relay 67, to ground. Relay 90 locks up through its left-hand armature and front contact and the inner left-hand armature and front contact of relay 10 87', and the back contact and armature of relay 88 to ground. When relay 69 is energized in response to the release of the listening-in key which has been depressed as previously described, a circuit is completed 15 from grounded battery, winding of relay 88, outer right-hand armature and front contact of relay 87', right-hand armature and front contact of relay 90, left-hand armature and front contact of relay 69, upper 20 armature and front contact of relay 67, to ground. Relay 88 is energized and breaks the circuit of counting relays 87 and 87' and the locking circuit of relay 90, and these relays deenergize. The deenergization of 25 relay 90 opens the circuit of relay 88 and it deenergizes in turn. While there is one call stored up and the operator is listening in on the first call, the position will still be maintained in a non-selectable condition, 30 due to the energized condition of relay 89, its circuit at this time extending from grounded battery, winding of relay 89, its right-hand armature and front contact, to ground at the armature and back contact of 35 relay 86.

When the operator depresses another listening-in key to listen in on the second call, relay 69 will be deenergized as previously described, but relay 67 will be maintained 40 energized. Therefore relay 90 will be energized over a circuit extending from grounded battery, winding of relay 90, right-hand armature and back contact of relay 69, upper armature and front contact of relay 67, to ground. Relay 90 locks up through its 45 left-hand armature and front contact and the inner left-hand armature and back contact of counting relay 87' and the outer armature and front contact of relay 84' to ground. As soon then as the second listening key which was depressed is released, relay 69 is energized and a circuit is completed 50 from grounded battery, winding of relay 86, outer right-hand armature and back contact of relay 87', right hand armature and front contact of relay 90, right-hand armature and front contact of relay 69, and the upper armature and front contact of relay 67, to ground. Relay 86 is energized in 55 this circuit and opens the locking circuits of relays 89, 84 and 84'. Relay 84' causes in turn the deenergization of relay 90, which causes the deenergization of relay 86. It will thus be seen that as soon as the operator

listened in on the second call, relay 89 deenergized allowing relay 18 to deenergize in turn and render the position again selectable. It is thus apparent that the operator's position is non-selectable when two calls have been stored up at her position and remains unselectable when one call is stored up at her position and she is listening in on a second call. As soon, however, as she has completed listening in on one of the calls, the position is again rendered selectable. 75

What is claimed is:

1. In an automatic telephone exchange system, a contact bank, multiple terminals of calling subscribers' lines arranged therein in groups and sub-groups, a line finder switch including a movable shaft carrying a plurality of sets of brushes, there being a set of brushes for each group of terminals, said brush sets being normally inoperative with respect to the groups of terminals to which they have access, means to advance said brush shaft into a position wherein one of said brush sets may be rendered operative with respect to the group of terminals served by it, means to advance an operated brush set in a sub-group selecting movement, and means to advance said operated brush set into engagement with the terminals of a calling line. 80

2. In an automatic telephone exchange system, a contact bank, multiple terminals of calling subscribers' lines arranged therein in groups and sub-groups, controlling apparatus individual to each of said groups, controlling apparatus individual to each of said sub-groups, a line finder switch including a movable shaft carrying a plurality of sets of brushes, there being a set of brushes for each group of terminals, said brush sets being normally inoperative with respect to the groups of terminals to which they have access, means to advance said brush shaft into a position wherein one of said brush sets may be rendered operative with respect to the group of terminals served by it, 100 means to determine the extent of such positioning movement in accordance with the condition of the controlling apparatus individual to the various groups, means to advance said operated brush set in a sub-group selecting movement in accordance with the condition of the controlling apparatus individual to the various sub-groups, and means to advance said operated brush set into engagement with the terminals of a 110 calling line. 115

3. In an automatic telephone exchange system, a contact bank, multiple terminals of calling subscribers' lines arranged therein in groups and sub-groups, controlling apparatus individual to each of said groups, controlling apparatus individual to each of said sub-groups, registering apparatus, means to

position such registering apparatus in accordance with the group and sub-group designation of the calling line, an automatic switch, means to advance said automatic switch in a group selecting movement in accordance with the setting of a certain one of said registers, means to advance said automatic switch in a group selecting movement directly controlled in accordance with the setting of said registering apparatus, means to advance said automatic switch in a sub-group selecting movement directly controlled in accordance with the setting of said registering apparatus, and means to advance said switch into engagement with the terminals of a calling line in the selected sub-group.

4. In an automatic telephone exchange system, a contact bank, multiple terminals of calling subscribers' lines arranged therein in groups, apparatus individual to each of said groups, a multi-position controlling switch, means to advance said controlling switch into a position determined by the group designation of the calling line, an automatic switch, means to advance said automatic switch in a group selecting movement, means to advance said multi-position switch in response to movement of said automatic switch to determine the extent of motion of said switch, and means to advance said automatic switch into engagement with the terminals of a calling line.

5. In an automatic telephone exchange system, a contact bank, multiple terminals of calling subscribers' lines arranged therein in groups and sub-groups, a multi-position switch, means to position said switch in accordance with the group designation of a calling line, registering apparatus, means to actuate said registering apparatus in accordance with the sub-group designation of said calling line, an automatic switch, means to advance said automatic switch in a group selecting movement under the control of said multi-position switch, said multi-position switch being advanced in response to movement of said automatic switch, means to advance said automatic switch in a sub-group selecting movement under the control of said multi-position switch in accordance with the setting of said registering apparatus, and means to advance said automatic switch into engagement with the terminals of the calling line.

6. In a call-distributing system, a plurality of operators' positions, a contact bank divided into sections, each section containing multiple terminals of calling subscribers' lines, a plurality of line finders serving each of said sections, means to extend a calling line to an operator's position, means to render the selectability of an operator's position dependent on the number of unanswered calls present at such position, means 6t controllable at said operator's position to start an idle line finder having access to the section in which the call originated, and means to operate said line finder to establish connection to a calling line.

7. In a call distributing system, a plurality of operators' positions, a contact bank divided into sections, each section containing multiple terminals of calling subscribers' lines, a plurality of line finders arranged to serve each of said sections, said line finders being arranged in groups, there being as many groups as there are operators' positions, means to select an idle operator's position in response to the initiation of a call, 75 means operative thereupon to start a line finder in the group which has access to such idle operator's position and which serves the section of contact bank in which the terminals of the calling line appear, and means 80 to advance said line finder into engagement with the terminals of the calling line.

8. In a call distributing system, a plurality of operators' positions, a contact bank divided into sections, each section containing 85 multiple terminals of calling subscribers' lines, a plurality of line finders arranged to serve each of said sections, said line finders being arranged in groups, there being as many groups as there are operators' positions, means operative thereupon to start a line finder in the group which has access to such idle operator's position and which serves the section of contact bank in which the terminals of the calling line appear, and means 90 to advance said line finder into engagement with the terminals of the calling line.

9. In a call distributing system, a plurality of operators' positions, a contact bank divided into sections, each section containing 95 multiple terminals of calling subscribers' lines, a plurality of line finders arranged to serve each of said sections, said line finders being arranged in groups, there being as many allotter switches associated with each operator's position, there being as many allotter switches at each position as there are sections of contact bank, each allotter being arranged to determine which line finder of a group shall be started, means to select an operator's position in response to the initiation of a call, means operative thereupon to start a line finder in the group which has access to such idle operator's position and which serves the section of contact bank in which the terminals of the calling line appear, and means to advance said line finder into engagement with the terminals of a calling line.

10. In a call distributing system, a plurality of operators' positions, a contact bank divided into sections, each section containing multiple terminals of calling subscribers' lines arranged in groups and sub-groups, a 11t plurality of line finders arranged to serve said section, said line finders being arranged in groups, there being as many groups as there are operators' positions, a plurality of allotter switches, registering and sending equipment associated with each of said allotter switches, means to select an idle operator's position in response to the initiation of a call, means operative to said selection to start an allotted line finder in the group 120 which has access to such idle operator's position, means to advance said line finder switch in group and sub-group selecting 125

movements under the control of an associated registering and sending equipment, and means to advance said line finder into engagement with the terminals of the calling line.

- 5 10. In a telephone exchange system, calling subscribers' lines, a plurality of operators' positions, means to extend a calling line to a selectable operator's position, a 10 counting device at said operator's position, means to actuate said counting device to record the number of unanswered calls present at said operator's position at a time, and means to render an operator's position non-selectable after a predetermined number of calls has been extended thereto.
- 15 11. In a telephone exchange system, calling subscribers' lines, a plurality of operators' positions, means to extend a calling line to a selectable operator's position, means to render an operator's position non-selectable after two calls have been extended thereto, means to maintain said position non-selectable while two unanswered calls appear at

said position, or while one unanswered call 25 is present and said operator is listening in on a second call, and means to render said position again selectable when one call only appears at said position.

12. In a telephone exchange system, calling subscribers' lines, a plurality of operators' positions, means to extend a calling line to a selectable operator's position, a controlling relay, a plurality of sets of counting relays at each operator's position, means to actuate said counting relays to record the number of unanswered calls at an operator's position, one set of counting relays being actuated for each unanswered call, means to actuate said controlling relay when a predetermined number of said sets of counting relays are actuated, and means controlled by said controlling relay to render the operator's position non-selectable.

In witness whereof I hereunto subscribe 45 my name this 27th day of March, A. D. 1917.

SAMUEL B. WILLIAMS, JR.
